(57) CLAIM

The ornamental design for a drawer pull, as shown and described.

DESCRIPTION

FIG. 1 is an isometric view of the drawer pull of the present invention, the broken line showing of a drawer is for illustrative purposes only and forms no part of the claimed design.

FIG. 2 is a front view of the drawer pull of the present invention, the broken line showing of a drawer is for illustrative purposes only and forms no part of the claimed design.

FIG. 3 is a vertical section view of the drawer pull shown in FIG. 2, the broken line showing of a drawer is for illustrative purposes only and forms no part of the claimed design; and, FIG. 4 is an enlarged view of the top of the vertical section view of the drawer pull shown in FIG. 3, the broken line showing of a drawer is for illustrative purposes only and forms no part of the claimed design.

The top, back and sides of the drawer pull are flat surfaces. The front of the drawer pull has a convex surface and there is an indentation on the underside of the drawer pull.
